UNITED STATES PATENT OFFICE.

GARY N. GRAY, OF SCRANTON, AND JOHN J. McNULTY, OF OLYPHANT, PENNSYLVANIA.

COAL-CHUTE.

1,254,625.

Specification of Letters Patent. Patented Jan. 22, 1918.

Application filed July 19, 1915. Serial No. 40,600.

To all whom it may concern:

Be it known that we, GARY N. GRAY and JOHN J. McNULTY, citizens of the United States, and residents of Scranton, Lackawanna county, State of Pennsylvania, and Olyphant, Lackawanna county, State of Pennsylvania, respectively, have invented certain new and useful Improvements in Coal-Chutes, of which the following is a specification.

The principal object of our invention is to provide a coal chute of such construction that by its use a minimum percentage of the coal is broken as it descends therein from a higher to a lower level.

A further object of our invention is to provide a construction of chute in which, while the coal is permitted to travel downwardly therein without becoming blocked or in any way interrupted, the speed of travel is so controlled and retarded that the coal is prevented from unnecessarily breaking into smaller particles. In this way a material decrease in the percentage of waste due to the breaking up of the coal into particles too small for certain uses is effected. This result is effected by use by reason of the fact that the coal is caused to descend in what may be described as a step by step movement. While the coal may be described as traveling downwardly in a spiral path such path is divided into a plurality of steps which are suitably arranged, one below the other as shown. In the construction shown four of these steps constitute a complete spiral or circle, but the number may be increased within certain limits if desired. The steps are arranged in succession one below the other and each succeeding step is arranged and inclined in a direction transverse to the arrangement and inclination of the immediately preceding step.

Other objects and advantages of our invention will be referred to in the detailed description thereof which follows or will be apparent from such description.

In the accompanying drawings we have illustrated one form of a convenient embodiment of our invention but it will be understood that changes in the details of construction may be made within the scope of the claims without departing therefrom.

In the drawings:—

Figure 1 is a perspective view of a coal chute embodying our invention;

Fig. 2 is a side elevational view thereof;

Fig. 3 is a top plan view of the same; and Fig. 4 is a perspective view of one of the steps employed in the construction of the chute.

Referring to the drawings, 1 designates a central column or post upon which the steps forming the chute are secured and supported. 2 designates a series of steps each of which is provided upon its inner side edge with a depending triangular flange 3 by means of which it is secured to a side of the post or column 1 by means of screws, bolts or other suitable fastenings. The outer end and outer side edge of each of the said steps are provided, respectively, with flanges 4 and 5. The bottom of each of the said steps is of angular shape in transverse section, as is clearly shown, that is to say, opposite portions 6 and 7 of the bottom of each of the said steps incline toward a diagonal line 8.

It will be observed upon reference to the drawings, particularly Fig. 3, that the steps are arranged successively with respect to each other and that the lower forward end of what may be termed the preceding step overlaps the inner side edge of the next succeeding step and that adjacent overlapping steps are arranged substantially at right angles to each other. It will also be observed from Fig. 3 that in the present construction four of these steps constitute a complete circle or spiral.

In order to render the structure rigid and for the purpose of holding the outer end and side portions of the steps in rigid fixed relation with respect to each other, we have provided angle irons 10 at the four corners of the chute, securing the same to the flanges 4 and 5 of the respective steps by means of bolts 11. By means of bolts 12 the flanges 4 and 5 of adjacent steps are fastened together which also adds to the strength and rigidity of the structure.

It will be understood that the chute may be constructed of such height as may be desirable by employing a greater or less number of the steps.

In the construction illustrated we have shown the steps arranged so that the coal travels around the post or column 1 in an anti-clockwise direction. Obviously the arrangement may be such that the coal is caused to travel in a clockwise direction without departing in any way from our invention.

In the use of a construction embodying our invention the coal is delivered on to the uppermost of the steps which we shall designate as *a* in Figs. 1 and 3 of the drawings. 5 The coal thus delivered travels downwardly in the direction of the arrow on the step *a* shown in Fig. 3 of the drawings. It is delivered therefrom on to the next succeeding step which we have designated *b*. It will 10 be seen that the coal when it is delivered on to the step *b* is traveling or moving substantially at right angles to the direction of inclination of the step *b*. It may be that the coal will strike the step *b* or any one of 15 the next succeeding steps with sufficient speed to travel beyond the diagonal line *S* (which is the meeting line between the angularly related sides 6 and 7 of the bottom of the respective steps) on to the upwardly inclined portion 7 of the said step. The coal having reached the step *b* changes its direction and moves downwardly thereon in the direction of the arrow substantially at right angles to the direction in which it traveled 20 downwardly over the step *a*. This action is repeated from the step *b* to the next succeeding step *c* and from the latter to the next succeeding step *d* and so on to the end of the chute. 25

30 We have demonstrated that as a result of delivering the coal downwardly in the chute step by step in the manner described, that is, by causing it to move downwardly in a series of successive rectilinear movements, 35 a great deal of the breakage and wastage due to such breakage is eliminated.

We claim:

1. A coal chute comprising a plurality of steps the opposite side portions of each 40 step being inclined toward a diagonal line extending from the upper toward the lower end thereof and the lower end of the bottom of each step overlapping the adjacent side edge of each succeeding step and means for 45 supporting the said steps in fixed relation to each other.
2. A chute for delivering coal or similar material from a higher to a lower level comprising a plurality of steps each of which is 50 provided with a plurality of flat portions, one of which portions is inclined downwardly at a selected angle and extended in the direction substantially at right angles to the direction of the immediately preceding and succeeding steps and the other of 55 which portions is inclined downwardly in the same direction at a less angle and is also inclined outwardly and upwardly from its point of junction with the other flat portion 60 in a direction transverse to the first men-

tioned inclination, substantially as described.

3. A chute for delivering coal or similar material from a higher to a lower level comprising a plurality of steps spirally arranged, each of said steps consisting of a flat portion inclined downwardly at a selected angle in a direction substantially at right angles to the direction in which the corresponding portions of the immediately preceding and succeeding steps extend and also a flat portion inclined downwardly at a less angle than the other flat portion and also inclined upwardly and outwardly from its line of junction with the first named flat portion and means for supporting the said steps, substantially as described. 65 70 75

4. A coal chute comprising a plurality of steps arranged in spiral relation, each step being adapted to discharge coal or similar material on the next succeeding step and each step being provided with means which tends to prevent the increase of the momentum of the coal in its travel toward the bottom of the chute. 80 85

5. A coal chute comprising a plurality of steps arranged in spiral relation, the said steps being arranged so that each of them extends in a direction substantially at right angles to the direction in which the next 90 preceding and succeeding steps extend and the said steps causing the coal or similar material to travel downwardly in corresponding directions and each comprising means for preventing the acceleration of the speed 95 of travel of the coal or other similar material as it moves downwardly in the chute, substantially as described.

6. A spiral chute or separator comprising a succession of plates each having two forwardly downwardly inclined portions meeting along a substantially diagonal line. 100

7. A spiral chute or separator comprising a succession of plates each having its face in two forwardly downwardly inclined 105 planes meeting along a substantially diagonal line.

8. A spiral chute or separator comprising a succession of plates each having its face in a plurality of forwardly downwardly inclined planes. 110

In testimony that we claim the foregoing as our invention we have hereunto signed our names this 14th day of July, A. D. 1915.

GARY N. GRAY.
JOHN J. McNULTY.
